UNITED STATES PATENT OFFICE.

JOHN RICHARDS, OF SAN FRANCISCO, CALIFORNIA.

METAL BORING AND SLOTTING MACHINE.

SPECIFICATION forming part of Letters Patent No. 299,496, dated May 27, 1884.

Application filed February 10, 1883. (No model.)

To all whom it may concern:

Be it known that I, JOHN RICHARDS, a citizen of the United States, residing at San Francisco, in the county of San Francisco and State of California, have invented certain new and useful Improvements in Metal Boring and Slotting Machines; and I do hereby declare the following to be a full, clear, and exact description of the invention, such as will enable others skilled in the art to which it appertains to make and use the same.

This invention relates to machines for turning and boring metals, commonly termed "boring-mills," and to adapting the same for cutting keyways or slotting.

The invention consists, mainly, in the means for giving the cutter-bars of such machines a reciprocating motion, that is derived from the same mechanism employed to feed the bars upward or downward in boring or turning, such mechanism being so arranged and driven in respect to strength and speed as to fill both requirements.

It also consists in the combination, with the saddles on such machines, of screws for imparting a lateral feed to said saddles, each saddle being provided with two nuts—one for each screw—so that by connecting the saddles to different screws at will the lateral feed of said saddles can be independent, and thus started, stopped, or reversed without changing the feed-driving gearing, or the rate of feed can be greater or less on either saddle, as the work may require.

I am aware that metal turning and boring machines have been arranged with a reciprocating motion of their cutter-bars for cutting keyways and similar work, but not in the manner of my invention, the driving-gearing, to produce such motion being heretofore independent of the feed-motion, and separate from other gearing of the machines. Such methods require the reciprocating mechanism to be engaged and disengaged, and are not operative for any but a vertical or nearly vertical stroke of the cutter-bars.

In the annexed drawings, illustrating my invention, Figure 1 is a front elevation of a common boring and turning machine with my improvements. Fig. 2 is an end view of the same. Fig. 3 is an enlarged section on the line $\alpha\alpha$ of

Fig. 1. Fig. 4 is a detail view showing the manner of operating the feeding mechanism of the saddles.

Like letters of reference indicate the same parts in the several views.

A is the main frame; B, the table or face-plate on which work is mounted, and P is a pulley in position to be slotted or grooved for a key.

a a are cutter-bars carrying tools b b for turning, boring, or slotting.

c c are saddles sliding on the cross-beam d, and carrying the spindles or cutter-bars a a.

e e are two screws—one right, the other left—employed for feeding the saddles either way upon the beam d and independently of each other, as hereinafter described.

f is a motion-rod employed for two purposes—one to feed the bars a a up or down in boring or turning, and the other to give these bars a rapid motion for cutting keyways or slotting. In the case of feeding the cutter-bars vertically, this rod or shaft f is driven from the gearing at g by any of the usual methods, a connection with the running table B or its gearing, as shown, for example, by dotted lines in Fig. 1, being preferable. This motion from the rod f is communicated to the bars a a by means of a worm and wheel, (shown at h i in Fig. 3, also 80 in dotted lines in Fig. 1,) each wheel h being provided with a hub or sleeve, h', through which passes a shaft, k, having a pinion, k', that engages with a rack, a', on the reciprocating cutter-bar. The worm-wheel h is loose 85 on the pinion-shaft k, but is connected in feeding the cutter-bars vertically by the cone clutch-plate m, hand-nut o, and rod p, as shown in Fig. 3. For vertical feeding the motion of this gearing is slow, the rod f making approximately as many revolutions as the table B; but for cutting keyways, as shown in Fig. 1, the gearing at g is disengaged from its driving-power and the belt-driving gearing at s s' is put in use. By this means the rod f is driven 90 at a much greater speed, the number of revolutions being, for example, one hundred times

more, and fast enough to produce through the gearing h i a reciprocating motion of the bars a a, corresponding to a common slotting or planing machine, from eight to twenty feet a minute, as the nature of the work may per-

mit. There are two bands applied at $s s'$ —one for the upstroke and one for the downstroke of the bars $a a$, the upstroke being more rapid, as in the case of planing or other reciprocating machines for metal-cutting. The bands are shifted by means of the lever t and rod v , by hand; or automatic shifting-gearing can be employed, as in the case of planing-machines, the principle of operation remaining the same in either case.

It will be observed that the saddles $c c$ are each provided with a rotary plate, c' , having a hub through which the sleeve h' and the pinion-shaft k are passed. The rotary plate c' is provided with guide-loops $c^2 c^2$, for the reciprocating cutter-bar.

In this manner it may be seen that the bars $a a$ can operate at any angle and for any range required in keyway-cutting, the added mechanism required for that purpose consisting only of the belt-driving gearing at $s s'$, and the vertical feeding parts constructed strong enough to sustain a rapid reciprocating motion. For traversing the saddles $c c$ and bars $a a$ on the beam or cross-head d , I employ two screws, $e e'$ —one right, the other left, or else alike, and revolving in opposite directions, which is practically the same thing. The saddles $c c$ can be connected with either of the screws by half-nuts w , in the usual manner, as shown in Fig. 4. The top and bottom parts, $y y$, of these nuts have no screw-threads, being only supporting-bearings, the nut z sliding between and engaging either the upper or the lower screw, according as the handle w' is moved up or down, so that the saddles $c c$ and bars $a a$ can move to the right or left independently when connected to different screws. These screws are each

provided with a spur-gear, as shown in Fig. 1, the upper screw being actuated by a spur-gear on the motion-rod f , and an idler-gear being arranged to mesh with the gears on each of said screw-shafts, to transmit motion from one to the other. These gears will be so arranged that they can be readily thrown out of mesh when it is not necessary to impart a lateral feed to the saddles.

It is obvious that the mechanism for driving the motion-rod f and screw-shafts $e e'$ can be varied without affecting the principle of my invention.

Having thus described my invention, what I claim as new, and desire to secure by Letters Patent, is—

1. The combination of the saddle c , reciprocating cutter-bar a , having rack a' , the motion-rod f , provided with worm-gear i , the worm-wheel h , cone-plate m , the shaft k , carrying pinion k' , the rod p , and nut o , substantially as shown and described. 55

2. The combination, with the saddles $c c$, carrying half-nuts w , and reciprocating cutters a , of the feed-screws $e e'$, and means for actuating the same, substantially as shown and described. 60

3. The combination of the saddles $c c$, reciprocating cutter-bars $a a$, having racks $a' a'$, the feed-screws $e e'$, motion-rod f , having worm-gear i , the worm-wheel h , pinion k' , and suitable connecting and actuating mechanism, substantially as shown and described. 65

In testimony whereof I affix my signature in presence of two witnesses.

JOHN RICHARDS.
